UNITED STATES PATENT OFFICE.

LEO C. KIEHNLE, OF ELIZABETH, NEW JERSEY, ASSIGNOR TO THE SINGER MANUFACTURING COMPANY, A CORPORATION OF NEW JERSEY.

STAND FOR SEWING-MACHINES.

1,306,763.

Specification of Letters Patent. Patented June 17, 1919.

Application filed September 21, 1918. Serial No. 255,091.

To all whom it may concern:

Be it known that I, LEO C. KIEHNLE, a citizen of the United States, residing at Elizabeth, in the county of Union and State of New Jersey, have invented certain new and useful Improvements in Stands for Sewing-Machines, of which the following is a specification, reference being had therein to the accompanying drawings.

10 This invention relates to stands for sewing machines of the unit type largely employed in factories supplied with electricity or equipped with machines for electrical generation.

15 In stands for sewing machines equipped with individual motors for the electrical operation of the machines, it has been found desirable to provide for manual operation by foot power when, for one cause or another, the flow of electrical energy is interrupted. The present invention aims to provide convenient and simple devices for expeditiously changing from electrical to foot-power operation without an unnecessary waste of time and without needlessly encumbering the machine. The invention also contemplates a disposition and arrangement of a motor, a rheostat and a driving fly-wheel which is compact and not un- 10 slightly.

In one form the invention comprises a standard fitted with a motor, a rheostat or starting box and a fly-wheel or driving pulley all arranged beneath the table which is supported by a frame between whose legs is arranged a treadle adapted to be connected by a pitman with either an operating switch of the rheostat or a crank on the fly-wheel or driving pulley. The pitman mentioned comprises a section articulated to the treadle, a second one piece section connected to the crank of the driving pulley and a third adjustable and bent section connected to the operating switch of the rheostat. The adjacent ends of the three pitman sections are suitably threaded, both of the second and third mentioned sections being externally threaded for reception by the internally threaded end of the first mentioned section. By connecting up the first-men-

tioned section of the pitman with one or the other of the two remaining sections of the pitman the sewing machine may be operated by foot power or by electrical energy as desired. When by reason of storms, 55 short-circuits or accidents the flow of electricity to the motor is interrupted, the operator may continue her work without any considerable loss of time by merely coupling the machine up for treadle opera- 60 tion by foot-power.

The invention is illustrated in the accompanying drawings in which Figure 1 is a rear view in perspective of a stand with a sewing machine head positioned thereon. Fig. 65 2 is an end elevation of the stand and Fig. 3 is a detail of a section of a pitman which is articulated to the foot-treadle.

As illustrated in the drawings, the machine head indicated at 1 rests upon a table 2 supported by the leg standards 3 which are connected by the brace 4. Between the leg standards 3 a foot-treadle 5 is pivotally supported within convenient reach of an operator's foot. Adjacent one of the leg standards 3 a driving pulley 6 with a crank 7 is rotatably supported in the frame.

By the table and therebeneath is supported a motor 8 having a belt-pulley 9 and a brake-wheel 10 on its rotor, the motor being 80 disposed between the driving pulley 6 and the remote leg standard 3. Adjacent the driving pulley 6 and on the opposite side of one of the leg standards 3 is a rheostat 11 of any suitable design having an operating lever or switch 12 for cutting out resistance and gradually increasing the flow of electrical energy to the motor through the wiring indicated at 13 and 14 when the machine is started up. A brake-shoe 15, 90 adapted to bear on the brake-wheel 10 fixed to the rod 16, is fulcrumed in the upper part of the rheostat or starting box and a spring 17 coiled about the rod tends to apply the brake to stop the operation of the rotor and 95 to simultaneously throw the starting switch 12 to a position in which the circuit is open.

On the shaft 20 in the sewing machine head is provided the usual hand-wheel 21 having a belt-groove 22 adapted to receive 100

either the belt 23 running to the motor 8 or the belt 24 running to the driving pulley 6.

The foot-treadle 5 is provided rearwardly with an ear 25 pierced to receive the socket 26 which is clamped thereto by the cup-ended screw 26' and jam-nut 26''. The socket 26 embraces the ball end 27 of one end of a pitman section 28 whose opposite end 29 is internally threaded. A second one-piece pitman section 30, strapped at 31 about the crank 7, has its lower end 32 externally threaded for disengageable connection with the internally threaded end 29 of the pitman section 28. A third pitman section 33, consisting of two rods adjustably held together by a clamp 34, is connected at its upper end through a crank-arm 35 on the rod 16 to the operating switch 12 of the rheostat and has its lower end 36 externally threaded for disengageable connection with the internally threaded end of the pitman section 28. One rod of this third pitman section 33 is bent intermediate its ends as indicated at 37 to clear the driving pulley 7. The pitman section 28 may be turned to connect it with either of the sections 31 and 33.

With the described construction and arrangement it will be seen that an interruption in the flow of electricity to the motor need cause the operator to lose no considerable time in awaiting the resumption of the flow because by merely disconnecting the section 33 of the pitman from the section 28 and connecting the latter with the section 30 of the pitman, the machine may be operated by foot-power, it being of course necessary also to unshift the motor-belt 23 from the groove 22 in the hand-wheel and substitute the pulley-belt 24. When either of the pitman sections 30 and 33 is disconnected, it hangs out of the way of the other pitman section.

Having thus set forth the nature of the invention, what I claim herein is:—

1. In combination, a stand for sewing machines including a table and a supporting frame comprising spaced leg standards and a brace connecting the same, a driving pulley supported between and adjacent one of the leg standards, a foot-treadle, a motor sustained beneath the table and located between the driving pulley and the other of said leg standards, a rheostat or starting box having an operating switch and located beneath the table outside of the leg standards and adjacent the driving pulley, wiring between a source of electrical energy and the rheostat and between the rheostat and the motor, a pair of driving belts which are adapted to operate the machine from the motor and from the driving pulley respectively, and a sectional pitman for actuation of either the driving pulley or the operating switch of the rheostat when it is de-

sired to operate the machine either manually or electrically.

2. In a stand for sewing machines, electrical and manual driving devices for operation of the machine by either electrical or 70 foot power including a treadle operated pitman having three sections one of which is adapted to be connected with either of the other two sections to enable the operator through the foot to manually operate the 75 machine or to govern its electrical operation.

3. In a stand for sewing machines, power and manual driving devices operatively arranged to operate the machine and including a foot-treadle, a pitman section articulated to the foot-treadle, and a pair of end-threaded pitman sections connected respectively to said power and manual driving devices and adapted to be connected to the first mentioned pitman section which is also 85 threaded at one end.

4. In combination, a stand for sewing machines including a table and a supporting frame comprising spaced leg standards and a brace connecting the same, a driving pulley supported between and adjacent one of the leg standards, a foot-treadle, a motor sustained beneath the table and located between the driving pulley and the other of said leg standards, a rheostat or starting 90 box having an operating switch and located beneath the table outside of the leg standards and adjacent the driving pulley, wiring between a source of electrical energy and the rheostat and between the rheostat and the 100 motor, a pair of driving belts which are adapted to operate the machine from the motor and from the driving pulley respectively, a pitman section at one end having a ball-and-socket connection with the foot-treadle and at its other end being threaded, a second one piece pitman section connected to the driving pulley, and a third adjustable pitman section operatively connected to the starting switch of the rheostat whereby the 110 machine through foot power may be operated manually or may be governed in its electrical operation.

5. In combination, a stand for sewing machines including a table and a supporting 115 frame comprising spaced leg standards and a brace connecting the same, a driving pulley supported between and adjacent one of the leg standards, a foot-treadle, a motor sustained beneath the table and located between the driving pulley and the other of said leg standards, a rheostat or starting box having an operating switch and located beneath the table outside of the leg standards and adjacent the driving pulley, wiring between a source of electrical energy and the rheostat and between the rheostat and the motor, a pair of driving belts which are adapted to operate the machine from the 120 motor and from the driving pulley respectively, and a sectional pitman for actuation of either the driving pulley or the operating switch of the rheostat when it is de-

tively, a pitman section at one end having a ball and socket connection with the foot-treadle and at its other end being threaded, a second one-piece pitman section connected to the driving pulley, and a third pitman section operatively connected to the starting switch of the rheostat whereby the machine through foot power may be operated manu-

ally or may be governed in its electrical operation, said third pitman section being 10 bent intermediate its ends to clear the driving pulley.

In testimony whereof, I have signed my name to this specification.

LEO C. KIEHNLE.
